VACUUM CLEANER HEAD ATTACHMENT

Edwin E. Robison, San Francisco, Calif.

Application September 8, 1952, Serial No. 308,478

2 Claims. (Cl. 15—246)

This invention relates in general to an attachment for 15 vacuum cleaners, and more specifically to a guard for a vacuum cleaner head.

The primary object of this invention is to provide an improved guard for attachment to a suction head of a vacuum cleaner, said guard being intended for use in the 20 cleaning of loop pile, shag, string or other similar type rugs and is adapted to engage the same to prevent the pulling thereof into the suction head of a vacuum cleaner.

Another object of this invention is to provide an improved suction head attachment in the form of a guard 25 for cleaning rugs and the like, said guard being so constructed and designed whereby the same may be quickly and easily attached to and removed from a suction head.

Another object of this invention is to provide an improved guard for suction heads of vacuum cleaners, said 30 guard being of a relatively simple construction and formed of inexpensive materials whereby the same is economical- ly feasible.

A further object of this invention is to provide an improved guard for attachment to a suction head of a vacuum cleaner over the inlet opening thereof, said guard being adapted to engage a surface being cleaned and having upwardly turned edge portions whereby movement over the surface being cleaned is facilitated.

With these objects definitely in view, this invention resides in certain novel features of construction, combination and arrangement of elements and portions as will be hereinafter described in detail in the specification, particularly pointed out in the appended claims, and illustrated in the accompanying drawings which form a material part of this application, and in which:

Figure 1 is a top plan view of a suction head for tank type vacuum cleaners and shows the guard, which is the subject of this invention, mounted thereon;

Figure 2 is a bottom plan view of the suction head of Figure 1 and shows the general relationship of the guard with respect to the same;

Figure 3 is a side elevational view of the suction head of Figure 1 and shows the general outline of the guard and the manner in which it is attached to the suction head;

Figure 4 is a top plan view of the guard per se and shows the manner in which it is constructed;

Figure 5 is a front elevational view of the guard of Figure 4 and shows the general configuration of the edge portions thereof; and

Figure 6 is a bottom plan view of a suction head for a tank type vacuum cleaner, said suction head having formed integral therewith a modified form of guard conforming to the spirit of this invention.

Similar characters of reference designate similar or identical elements and portions throughout the specification and throughout the different views of the drawings.

Referring now to the drawings in detail, it will be seen that there is illustrated in Figures 1, 2 and 3 a suction head for a tank type vacuum cleaner, said suction head

2

being referred to in general by the reference numeral 10. The suction head 10 is in the form of a concave housing which is generally elliptical in outline and which has an enlarged inlet opening 12 in the lower end thereof. Secured to the top of the suction head is a fitting 14 for attachment to a flexible vacuum cleaner hose or the like.

In order that material may be prevented from being sucked up into the inlet opening 12, there is provided a 10 detachable guard, which is the subject of this invention, the guard being referred to in general by the reference numeral 16.

Referring now to Figure 4 in particular, it will be seen that the guard 16 includes a one-piece guard member 18 which is formed of wire and bent to have a sinusoidal configuration. The guard member 18 includes a plurality of fingers 20 which are disposed at slight angles to their adjacent fingers and connected thereto by arcuate connecting portions 22. It will be noted that the guard member 18 also includes end fingers 24 which are substantially one-half the length of the other fingers 20 and which terminate in inwardly directed end portions 26. The end portions 26 are secured to adjacent fingers 18 against which they abut.

In order to facilitate the attachment of the guard member 18 to a suction head, such as the suction head 10, and also to reinforce the guard member, the guard 16 includes a pair of longitudinally extending stiffening members 28 and 30. The stiffening members 28 and 30 overlie the fingers 20 and 24 adjacent the ends thereof and are rigidly secured thereto.

Inasmuch as the end fingers 24 terminate substantially at the center line of the guard member 18, the stiffening member 28, which overlies the end fingers 24, is longer than the stiffening member 30. However, inasmuch as it is intended that the stiffening members 28 and 30 engage side edges of the suction head 10, or a similar suction head, the two stiffening members have the same general curvature and are in spaced relation.

It will be noted that the mid-point of the stiffening member 28 is formed with an integral upwardly projecting loop 32, and that the stiffening member 30 is provided with a pair of such loops equally spaced from the center of the same, the pair of loops being referred to by the reference numeral 34.

Referring now to Figures 1 and 3 in particular, it will be seen that when it is desired to position the guard 16 on the bottom of the suction head 10 over the inlet opening 12, the guard 16 is moved into engagement with the bottom of the suction head 10 with the stiffening members 28 and 30 engaging opposite sides thereof. When so engaged on the suction head 10, the guard 16 is prevented from moving either longitudinally or transversely of the suction head. In order that the guard 16 may be prevented from dropping off of the suction head 10, there is provided securing means in the form of a pair of tension springs 36 which overlie the top of the suction head 10 on opposite sides of the fitting 14 and which have one end connected to the loop 32. The other end of each of the tension springs 36 is connected to one of the loops 34.

It will be noted that the guard member 18 has the fingers thereof disposed below the suction head 10 and the same are intended to glidingly engage a surface, such as a rug, that is to be cleaned. In order that the movement of the guard member 18 over the surface to be cleaned may be facilitated, the end portions of the fingers 20 and 24, including the connecting portions 22 are curved upwardly, as is best illustrated in Figures 3 and 5. However, it will be noted that the intermediate portions of the fingers 20 and 24 are flat and lie in a com-

mon plane so as to permit flush engagement with a surface being cleaned.

Referring now to Figure 6 in particular, it will be seen that there is illustrated a modified form of guard which is referred to in general by the reference numeral 40. The guard 40 is intended for use with a suction head for a tank-type vacuum cleaner, said suction head being referred to in general by the reference numeral 42. The suction head 42 is substantially identical to the suction head 10 and includes an inlet opening 44 on the bottom thereof and an outlet fitting 46 carried at the top thereof. The guard 40 also has a sinusoidal outline and is formed of a single piece of material. However, the guard 40 differs from the guard 16 in that it is a one-piece member and is secured directly to the portion of the suction head surrounding the inlet opening 14 and is not removable therefrom.

While the guards 16 and 40 have been illustrated and described as being associated with suction heads of tank-type vacuum cleaners, it will be understood that the invention is not intended to be so limited. If desired, the guards 16 and 40, with a slight change in outline, may be secured to inlet openings of suction heads of upright type vacuum cleaners.

A suction head, when provided with either the guard 16 or the guard 40, may be utilized for the quick and efficient cleaning of rugs and like surfaces. During the cleaning operation, the guards hold the material down while the vacuum removes the dirt particles from the base and the top of the rug. The upwardly curved edges of the guards allow the guards to pass over the material without catching in the loops thereof. While the guards will hold the material down, will also cause the loops of material to be fluffed up by allowing the loops to be pulled up between the fingers of the guards giving the rug the appearance and quality of being renewed. This is also achieved by the alternate passing of the loops of the rug through the spaces between the fingers of the guards which gives a combing action to the material of the rug.

The operation of this device will be understood from the foregoing description of the details thereof, taken in connection with the above recited objects and drawings. Further description would appear to be unnecessary.

Minor modifications of the device, varying in minor details from the embodiment of the device illustrated and described here, may be resorted to without departure from

the spirit and scope of this invention, as defined in the appended claims.

Having described the invention, what is claimed as new is:

- 5 1. A guard for a vacuum cleaner suction head comprising a guard member sinusoidal in plan and having a generally rectangular outline and adapted to be detachably secured across an inlet opening of a vacuum cleaner suction head, said guard member including a plurality of fingers connected together by spaced arcuate connecting portions, transversely spaced longitudinally extending stiffening members disposed generally normal to said fingers and secured at spaced intervals to said guard member and reinforcing the same, securing means connected to said stiffening members for overlying a vacuum cleaner suction head and clampingly retaining said guard member in position, said stiffening members being spaced and configurated for engaging side edges of a suction head.
- 10 2. A guard for a vacuum cleaner suction head comprising a guard member sinusoidal in plan and having a generally rectangular outline and adapted to be detachably secured across an inlet opening of a vacuum cleaner suction head, said guard member including a plurality of fingers connected together by spaced arcuate connecting portions, transversely spaced longitudinally extending stiffening members disposed generally normal to said fingers and secured at spaced intervals to said guard member and reinforcing the same, securing means connected to said stiffening members for overlying a vacuum cleaner suction head and clampingly retaining said guard member in position, said stiffening members being spaced and configurated for engaging side edges of a suction head.
- 15 3. A guard for a vacuum cleaner suction head comprising a guard member sinusoidal in plan and having a generally rectangular outline and adapted to be detachably secured across an inlet opening of a vacuum cleaner suction head, said guard member including a plurality of fingers connected together by spaced arcuate connecting portions, transversely spaced longitudinally extending stiffening members disposed generally normal to said fingers and secured at spaced intervals to said guard member and reinforcing the same, securing means connected to said stiffening members for overlying a vacuum cleaner suction head and clampingly retaining said guard member in position, said stiffening members having offset intermediate portions receiving said securing means, said stiffening members being spaced and configurated for engaging side edges of a suction head.
- 20 4. A guard for a vacuum cleaner suction head comprising a guard member sinusoidal in plan and having a generally rectangular outline and adapted to be detachably secured across an inlet opening of a vacuum cleaner suction head, said guard member including a plurality of fingers connected together by spaced arcuate connecting portions, transversely spaced longitudinally extending stiffening members disposed generally normal to said fingers and secured at spaced intervals to said guard member and reinforcing the same, securing means connected to said stiffening members for overlying a vacuum cleaner suction head and clampingly retaining said guard member in position, said stiffening members having offset intermediate portions receiving said securing means, said stiffening members being spaced and configurated for engaging side edges of a suction head.
- 25 5. A guard for a vacuum cleaner suction head comprising a guard member sinusoidal in plan and having a generally rectangular outline and adapted to be detachably secured across an inlet opening of a vacuum cleaner suction head, said guard member including a plurality of fingers connected together by spaced arcuate connecting portions, transversely spaced longitudinally extending stiffening members disposed generally normal to said fingers and secured at spaced intervals to said guard member and reinforcing the same, securing means connected to said stiffening members for overlying a vacuum cleaner suction head and clampingly retaining said guard member in position, said stiffening members having offset intermediate portions receiving said securing means, said stiffening members being spaced and configurated for engaging side edges of a suction head.
- 30 6. A guard for a vacuum cleaner suction head comprising a guard member sinusoidal in plan and having a generally rectangular outline and adapted to be detachably secured across an inlet opening of a vacuum cleaner suction head, said guard member including a plurality of fingers connected together by spaced arcuate connecting portions, transversely spaced longitudinally extending stiffening members disposed generally normal to said fingers and secured at spaced intervals to said guard member and reinforcing the same, securing means connected to said stiffening members for overlying a vacuum cleaner suction head and clampingly retaining said guard member in position, said stiffening members having offset intermediate portions receiving said securing means, said stiffening members being spaced and configurated for engaging side edges of a suction head.
- 35 7. A guard for a vacuum cleaner suction head comprising a guard member sinusoidal in plan and having a generally rectangular outline and adapted to be detachably secured across an inlet opening of a vacuum cleaner suction head, said guard member including a plurality of fingers connected together by spaced arcuate connecting portions, transversely spaced longitudinally extending stiffening members disposed generally normal to said fingers and secured at spaced intervals to said guard member and reinforcing the same, securing means connected to said stiffening members for overlying a vacuum cleaner suction head and clampingly retaining said guard member in position, said stiffening members having offset intermediate portions receiving said securing means, said stiffening members being spaced and configurated for engaging side edges of a suction head.
